UNITED STATES PATENT OFFICE.

HOWARD BIGELOW, OF KALAMAZOO, MICHIGAN. ASSIGNOR OF ONE-HALF TO BERTON E. GRANGER, OF KALAMAZOO, MICHIGAN.

GLOVE.

Application filed September 12, 1921. Serial No. 499,900.

To all whom it may concern:

Be it known that I, HOWARD BIGELOW, a citizen of the United States, residing at the city and county of Kalamazoo, State of Michigan, have invented certain new and useful Improvements in Gloves, of which the following is a specification.

This invention relates to improvements in gloves.

10 The main object of this invention is to provide an improved glove which may be used in signaling or in work requiring illumination, and one which may be operated while the user is grasping an object.

15 Further objects, and objects relating to structural details, will definitely appear from the detailed description to follow.

20 I accomplish the objects of my invention by the devices and means described in the following specification. The invention is clearly defined and pointed out in the claim.

25 A structure which is a preferred embodiment of my invention is clearly illustrated in the accompanying drawing, forming a part of this application, in which:

Fig. I is a rear view of my improved glove partially broken away to disclose the battery within its supporting pocket.

30 Fig. II is an enlarged detail section through the first and second fingers of the glove illustrating the mounting of the circuit closing contact members thereon.

35 Fig. III is an enlarged detail section on a line corresponding to line 3—3 of Fig. I, showing the mounting of the lamp.

In the drawing similar reference characters refer to similar parts throughout the several views.

Referring to the drawing, the glove 1 is 40 of the gauntlet type, a pocket 2 being provided on the sleeve portion thereof to receive the battery 3. In the back of the glove is a socket 4 for the bulb 5, the socket being mounted on a lining 6, while the bulb is disposed through an opening 7 in the back of the glove, the bulb only being exposed.

On the first and second fingers of the glove I mount contact closing members 8.

These are connected in circuit with the battery and lamp by the wires 9. The contact members 8 are disposed in opposed relation on adjacent fingers, preferably the first and second fingers of the hand, as illustrated, but normally out of alignment, that is, they are not in the same plane longitudinally of the fingers when the fingers are in normal position, but are in the same plane transversely of the fingers so that they may be brought into engagement by a swinging movement of the fingers while grasping an object.

My improved glove is well adapted for use in signaling as for a motor vehicle driver. It is also desirable for use in work that requires illumination, as the user may 65 grasp an object in the usual way and a slight swinging movement of the fingers will bring the contacts into engagement, so that it is unnecessary to release an object or lay down a package which one may be 70 carrying; for instance, it may be used to illuminate a key-hole without laying down a package which may be held in the hand.

My improved glove is very convenient to use and is also simple and economical in 75 structure.

Having thus described my invention, what I claim as new and desire to secure by Letters Patent, is:

The combination with a glove, of a battery mounted on said glove, an electric lamp mounted on said glove, and a pair of contacts operatively connected to said battery and lamp and disposed on the facing sides of the adjacent fingers in the same plane 80 perpendicular to the extended fingers but in different planes parallel to the plane of the extended fingers, so that said contact fingers are normally out of contact but may be 85 brought into contact by movement of the 90 fingers relative to the plane of the extended fingers.

In witness whereof, I have hereunto set my hand and seal.

HOWARD BIGELOW. [L. S.]
